UNITED STATES PATENT OFFICE.

FRANK E. SEELEY, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

DESIGN FOR AN ELECTRIC-SWITCH HANDLE.

41,494.

Specification for Design. Patented June 20, 1911.

Application filed February 4, 1911. Serial No. 606,658. Term of patent 14 years.

To all whom it may concern:

Be it known that I, FRANK E. SEELEY, a citizen of the United States of America, residing in the city of Bridgeport, in the county of Fairfield, in the State of Connecticut, have invented a new, original, and ornamental Design for an Electric-Switch Handle, of which the following is a specification, reference being had to the accompanying drawing, forming part thereof.

The figure is a perspective view of an electric switch handle, showing my new design.

I claim:

The ornamental design for an electric switch handle, as shown.

FRANK E. SEELEY.

Witnesses:

H. M. WICHERT,
L. B. WHEELER.
